CLASP FOR NECKLACES AND THE LIKE

Frank Joseph Maier, Irvington, N. J., assignor to
 Harry C. Schick, Inc., Newark, N. J., a corpora-
 tion of New Jersey

Application November 15, 1949, Serial No. 127,417

4 Claims. (Cl. 24—230)

1

This invention relates to improvements in clasps for releasably connecting together the ends of necklaces and like articles.

The invention has for an object to provide an improved construction of clasp body constituting the female member of a clasp structure, said clasp body being produced from a single or one-piece blank of sheet metal adapted to be wrought into finished form, and which includes self-contained fastener means whereby its parts, when brought into body forming relation, can be firmly secured against displacement from such relation, without necessity for use of soldered joints or other independent fastening means.

Other objects of the invention will be disclosed in the following detailed description of the same.

An illustrative embodiment of this invention is shown in the accompanying drawings, in which:

Fig. 1 is a plan view of a clasp body made according to the invention; Fig. 2 is a side elevational view of the same; Fig. 3 is a longitudinal sectional view of the clasp body, taken on line 3—3 in Fig. 1; Fig. 4 is a transverse vertical sectional view, taken on line 4—4 in Fig. 1; and Fig. 5 is an end elevational view of the male clasp member receiving end of the clasp body.

Fig. 6 is a plan view of the sheet metal blank from which the novel clasp body of this invention is formed.

Similar characters of reference are employed in the above described views, to indicate corresponding parts.

Referring to the drawings, the novel clasp body, which constitutes the female member of a separable clasp structure, is formed from a single or one piece flat sheet metal blank illustrated in Fig. 6. This blank is shaped to provide a front face section 10 and a back face section 11 which are joined at opposed ends by an outer end wall section 12. Integral with and extending laterally from opposite side margins of one of said face sections, preferably from the front face section 10, are side wall sections 13. Extending from the free end margin of the back face section 11 is an inner end wall forming panel 14 from which extends a neck section 15; said neck section 15 terminates in a perforate coupler piece 16 extending outwardly therefrom in the plane thereof. Extending from the free end margin of the front face section 10 is an inner end wall panel 17; said inner end wall section terminates in fastener or clip section 18 having freely extending, lateral clinching tongues 19 projecting from the sides thereof.

In folding the blank so as to form the clasp

2

body therefrom, the inner end wall panels 14 and 17 are respectively inturned to extend right-angularly to the planes of the front and back face sections 10 and 11 with which they are respectively connected, and the neck section 15, with the coupler piece 16, and the fastener or clip section 18, with its clinching tongues 19, are respectively turned to extend from said inturned end wall panels 14 and 17 in planes parallel to the planes of the front and back face sections 10 and 11. The side wall sections 13 are also inturned to extend right angularly to the plane of the front face section 10.

After the parts of the blank have been initially disposed in the above described positions, the back face section 11 is turned to extend right angularly to the outer end wall section 12, and the front wall section 10 is likewise turned to extend right angularly to the outer end wall section 12, and thus into spaced overlying relation to said back face section 11, with said outer end wall section 12 extending perpendicularly between said face sections. When the face sections 10 and 11 are thus superposed, the inner end wall panels 14 and 17 will meet in aligned relation perpendicular to the face sections, and the fastener or clip section 18 will be brought into meeting overlying relation to the neck section 15. At the same time, the side wall sections 13 will also be disposed to extend perpendicularly between side marginal portions of the face sections, and so that their free edges are positioned to abut the inner surface of the back face section 11 at side marginal portions thereof. The parts as thus disposed will now form a hollow clasp body adapted to receive insertion therein of the male clasp member (not shown) of the clasp structure of which the clasp body forms the female member. The outer end wall section 12 is provided with a suitably shaped aperture 20 through which the male clasp member may be passed to releasably engage it with the clasp body, all in manner already well known to the art.

45 To secure the parts of the clasp body in the body forming relations above described, and so as to be firmly held against displacement therefrom, the clinching tongues 19 are turned around the side edges of the neck portion 15 and then 50 bent inward into underlying clinched relation to the latter. In this manner, the clasp body parts are strongly interlocked against separation by the self-contained fastening means, thus avoiding necessity for use of soldering or like opera-

3

tions, or use of any other form of independent fastening means.

From the above it will be understood that this invention provides a very strong and durable clasp body which can be rapidly and easily produced at low cost and low labor expenditure.

Having now described my invention, I claim:

1. In a clasp structure, a female member provided by a body formed from a one-piece sheet metal blank, said body comprising a front face section and a back face section disposed in superposed spaced apart relation and joined at one end by an apertured outer end wall, said face sections each having inturned inner end wall panels meeting in aligned perpendicular extension therebetween, a neck section extending outwardly from one said inner end wall panel in plane parallel to the planes of said face sections, a clip section extending outwardly from the other inner wall panel to overlie the neck section in meeting relation thereto, one of said latter sections having a perforate coupler member extending therefrom, and said clip section having clinching tongues extending laterally from opposite sides thereof which are bent around into clinched embracing relation to said neck section.

2. In a clasp structure, a female member provided by a body formed from a one-piece sheet metal blank, said body comprising a front face section and a back face section disposed in superposed spaced apart relation and joined at one end by an apertured outer end wall, one of said face sections having inturned side wall sections perpendicular thereto with their free ends abutting the other face section, said face sections each having inturned inner end wall panels meeting in aligned perpendicular extension therebetween, a neck section extending outwardly from one said inner end wall panel in plane parallel to the planes of said face sections, a clip section extending outwardly from the other inner wall panel to overlie said neck section in meeting relation thereto, one of said latter sections having a perforate coupler member extending therefrom, and said clip section having clinching tongues extending laterally from opposite sides thereof which are bent around into clinched embracing relation to said neck section.

4

3. In a clasp structure, a female member provided by a body formed from a one-piece sheet metal blank, said body comprising a front face section and a back face section disposed in superposed spaced apart relation and joined at one end by an apertured outer end wall, said back face section having an inturned inner end wall panel, said front face section also having an inturned inner end wall panel, said panels meeting in aligned perpendicular extension between said face sections, a neck section extending right angularly outward from the end wall panel of the back section and terminating in a perforate coupler member extending outwardly therefrom in the plane thereof, a clip section extending right angularly outward from the end wall panel of the front section in superposed relation to said neck section, and said clip section having clinching tongues extending laterally from opposite sides thereof which are bent around into clinched embracing relation to said neck section.

4. In a clasp structure, a female member provided by a body formed from a one-piece sheet metal blank, said body comprising a front face section and a back face section disposed in superposed spaced apart relation and joined at one end by an apertured outer end wall, said front face section having inturned side wall sections perpendicular thereto with their free ends abutting the back face section, said back face section having an inturned inner end wall panel, said front face section also having an inturned inner end wall panel, said panels meeting in aligned perpendicular extension between said face sections, a neck section extending right angularly outward from the end wall panel of the back section and terminating in a perforate coupler member extending outwardly therefrom in the plane thereof, a clip section extending right angularly outward from the end wall panel of the front section in superposed relation to said neck section, and said clip section having clinching tongues extending laterally from opposite sides thereof which are bent around into clinched embracing relation to said neck section.
